Charles J. Severance.

ATTORNEY

UNITED STATES PATENT OFFICE.

CHARLES J. SEVERANCE, OF WACOUSTA, MICHIGAN.

DESK-DRAWER.

1,228,067.

Specification of Letters Patent. Patented May 29, 1917.

Application filed August 15, 1916. Serial No. 115,025.

To all whom it may concern:

Be it known that I, CHARLES J. SEVERANCE, citizen of the United States, residing at Wacousta, in the county of Clinton and 5 State of Michigan, have invented certain new and useful Improvements in Desk-Drawers, of which the following is a specification.

This case relates to desk drawers, and 10 more particularly to a drawer specially adapted to be used in connection with desks having inclined tops.

One of the main objects of the invention is to provide a drawer of the character 15 stated which will not slide out of its casing by gravity due to vibration or other causes. A further object is to provide a drawer of simple construction and operation which can be readily secured in any desired adjustment. Further objects will appear from the detail description.

In the drawings:

Figure 1 is a longitudinal vertical sectional view through the drawer as applied 25 taken in a plane near one side of the drawer.

Fig. 2 is a transverse section taken on the line 2—2 of Fig. 1.

Fig. 3 is a transverse section through the 30 drawer and its casing looking rearward taken on a line slightly in advance of the stirrup for limiting outward movement of the drawer.

Fig. 4 is a fragmentary underneath view 35 of the drawer.

Fig. 5 is a fragmentary plan view of the drawer casing showing the rack portion of the same.

The numeral 1 designates the downwardly 40 and forwardly inclined top of a desk. To the under face of this top, near one end thereof, are secured two parallel supporting strips 2. These strips are provided with horizontally extending rabbets adapted to 45 receive the laterally projecting flanges 3 at the upper edges of the side walls 4 of the rectangular drawer casing 5. This casing is also provided, at the upper edges of its side walls, with inwardly projecting flanges 50 3^a. A drawer 6 of rectangular cross section

is slidably mounted in the casing 5. This drawer is provided, near its inner end 6^a, with a transversely extending partition 7. The drawer is provided with a similar partition 8 near its front end. These partitions, 55 and the side walls 9 of the drawer, support the drawer bottom 10 in spaced relation to the bottom 11 of the drawer casing 5.

The partitions 7 and 8 are provided, near their lower ends, with apertures 7^a and 8^a, 60 respectively. These apertures are positioned near one side of the drawer and rockably support a longitudinally extending locking rod 12. The inner portion of this bar is turned inward at right angles, as at 13, and is then bent downward at right angles to form an engaging latch 13^a. The portion 13 and latch 13^a are positioned in the space between the inner end 6^a of the drawer and the partition 7 so as to be movable vertically 70 without engaging the contents of the drawer. At its outer end the rod 12 is turned inward at right angles as at 14 and is then bent outward at right angles as at 14^a. The outer end of the portion 14^a projects into a slot 75 15 through a plate 16, near the lower end thereof. This plate is provided, at its side edges, with integral longitudinally extending sleeves 17. These sleeves are slidably mounted on guide rods 18 secured to the outer end 80 6^b of the drawer in spaced relation to the inner base thereof. A thumb knob 19 is secured to plate 16 by means of a screw 20 threaded therein and passed through the plate. This screw extends through a vertical slot 21 in the front wall of the drawer. A fixed abutment or knob 22 is secured to 85 the front wall of the drawer in vertical alinement with the thumb knob 19.

A coil spring 23 is mounted about the 90 rod 12 adjacent the front partition 8 of the drawer. The forward end of this spring is extended laterally to form a finger 23^a which rests against the bottom 10 of the drawer so as to prevent uncoiling of the spring. The 95 inner end of the spring is secured to the rod by being passed through an aperture 24 therethrough. This spring acts to rotate the bar downwardly and inwardly so as to force the latch member 13^a at the inner end 100

2

thereof downward. The downward movement of the latch member is positively limited by a stop pin 25 secured in the inner partition 7 and projecting beneath the horizontal portion 13 of the bar.

5 The bottom 11 of the drawer casing is provided, at its transverse center, with a longitudinally extending series of spaced recesses 26 of arcuate shape. These recesses 10 constitute in effect a rack bar adapted to be engaged by the latch member 13^a of rod 12. When the latch member is in engagement with one of the recesses the drawer is locked against movement in its casing so as to be 15 secured in adjustment therein. When it is desired to open or close the drawer the thumb knob 19 is raised. This raises the plate 16 which, because of its connection with the portion 14^a of the rod, rotates the 20 rod so as to raise latch member 13^a out of engagement with the recesses 26. With the latch member in inoperative position the drawer may be moved in or out of its casing as desired. As soon as the thumb knob 25 is released the spring 23 acts to return the latch member 13^a to operative position so as to lock the drawer against movement. It will be evident that, by this construction, the drawer is prevented from sliding 30 out of its casing while it may be quickly and easily opened or closed, as desired. Also, by having the recesses 26 of arcuate shape and with vertical inner and outer walls, the drawer cannot be moved inward without 35 raising the latch member into inoperative position. This renders it impossible to force the drawer inward so as to create a loud noise such as would occur if a ratchet bar of ordinary construction with rearwardly 40 inclined teeth were used. This feature is of importance as eliminating all possibility of the creation of unnecessary noise by school children, as this invention is intended especially for use in connection with school 45 desks. This drawer provides a receptacle for holding the pencils, pens, and similar instruments used by the pupils in such a manner as to be readily accessible while, as above noted, completely eliminating all possibility of the creation of unnecessary noise.

50 In order to prevent withdrawal of the drawer from the casing, a limiting U-member or stirrup is suspended from the top edges of the sides of the casing with its horizontal bar 27 and arms 28 inside of the drawer. The arms 28 are turned outward at right angles at their upper ends to form suspending arms 29 which are loosely mounted through apertures through the casing 55 walls. Each of the arms 29 has its outer portion turned downward at right angles to provide stop members 30. These members are adapted to engage the under faces of the flanges 3 at the top edges of the walls 60 65 4 of the casing so as to prevent rotation of

the stirrup about its pivotal arm 29 beyond a predetermined point. By this means the stirrup cannot be rotated rearwardly and upwardly so as to be raised out of position to engage the inner partition 7 of the 70 drawer. One of the stops 30 is adapted to engage a lug 31 formed integral with and projecting from one side of the casing. This prevents forward rotation of the stirrup beyond a predetermined point so as to render 75 it impossible to rotate the stirrup outward and upward into inoperative position. By this means the drawer, while it may be slidably adjusted in its casing, is prevented from being entirely withdrawn from the same. 80

There may be slight changes made in the construction and arrangement of the various parts of my invention without departing from the field and scope of the same, and I intend to include all such changes, as fall 85 within the scope of the appended claims, in this application in which a preferred form only of my invention is disclosed.

What I claim, is:—

1. In a device of the character stated, a 90 casing provided in the inner face of its bottom with a longitudinally extending series of recesses, a drawer slidably in said casing, a locking rod rockably supported by the drawer beneath the bottom thereof, the inner 95 end of said rod being bent to engage into said recesses when the rod is depressed, and means for operating the rod exteriorly of the drawer.

2. In a device of the character stated, a 100 casing provided in the inner face of its bottom with a longitudinally extending series of recesses, a drawer slidable in said casing, a locking rod rockably supported by the drawer beneath the bottom thereof and having its inner end bent to engage into said 105 recesses when the rod is depressed, means for normally holding said rod depressed, a thumb knob slidably mounted on the front of said drawer, and connections between 110 said knob and rod for raising the rod out of engagement of said recesses when the knob is raised.

3. In a device of the character described, the combination of a casing provided with a 115 plurality of recesses in its bottom, a drawer slidable in the casing and having its bottom in spaced relation to the bottom of the casing, said drawer being provided with a transverse partition spaced from each end 120 wall, a rod carried by the drawer and rockably mounted therein between the bottom of the drawer and the bottom of the casing, said rod being provided at its inner end with an integral latch member positioned 125 between the inner end and the inner partition of the drawer and adapted to engage the said recesses in the bottom of the casing, a coil spring mounted about the rod and adapted to normally hold the latch member 130

in depressed position, a plate slidably mounted on the front wall of the drawer, means for moving the plate vertically, and connections between the said plate and the outer end of the rod whereby the rod is rotated so as to lift the latch member into inoperative position when the plate is raised.

In testimony whereof I affix my signature in presence of two witnesses.

CHARLES J. SEVERANCE.
